UNITED STATES PATENT OFFICE

93,603

DESIGN FOR A CASKET

William H. Blackford, Detroit, Mich.

Application May 16, 1934, Serial No. 51,812

Term of patent 7 years

To all whom it may concern:

Be it known that I, WILLIAM H. BLACKFORD, a citizen of the United States, residing at Detroit, in the county of Wayne and State of Michigan, have invented a new, original, and ornamental Design for a Casket, of which the following is a specification, reference being had to the drawing wherein the figure represents a perspective view of the article.

As illustrated, the predominating characteristics of the new design are its greater compact-

ness and simplicity by reason of the elimination of the usual frame member customarily extending around the periphery of the casket between the top panel and the ledge of the casket, and the diagonal cut extending across and dividing the top panel into two independent sections.

I claim:

The ornamental design for a casket, as shown and described.

WM. H. BLACKFORD.
